UNITED STATES PATENT OFFICE

ANTHONY PINTO, OF NEW YORK, N. Y., ASSIGNOR TO OTIS ELEVATOR COMPANY, OF JERSEY CITY, NEW JERSEY, A CORPORATION OF NEW JERSEY

CONTROL SYSTEM

Original application filed April 2, 1926, Serial No. 99,259. Divided and this application filed October 7, 1927. Serial No. 224,652.

The invention relates to control systems, and particularly to control systems for elevators.

This application is a division of application Serial No. 99,259, filed April 2, 1926.

As the art of elevators has developed, various improvements have greatly increased the efficiency of operation of the elevator systems over those of the earliest types. Among these 10 improvements have been those designed to reduce the time required to effect the completion of certain operations. One operation in which time is an important factor, particularly in high speed elevator systems, is that 15 of bringing the car to a stop at the landings. Where time is lost in making each stop, it will be seen, upon consideration of the total time lost during a day's operation or even during a single round trip, that the operating 20 efficiency of the system as a whole is considerably impaired. Self-leveling mechanism, which has been provided in many elevator systems in recent years for bringing the car to a level with the desired landing in 25 stopping, regardless of whether it under-runs or overruns the landing, has for one of its features a reduction in the time required to bring the car to an accurate stop at the landing.

30 Where self-leveling apparatus is employed in elevator systems wherein a direct current electric motor is used for raising and lowering the car and wherein power is supplied to the motor from a direct current variable voltage generator, the control of the field strength of the generator must be such that the E. M. F. generated may be rapidly brought to the desired values for obtaining the various leveling operations. Upon the occurrence of an 35 overrun in such systems, it is advantageous to reverse the polarity of the E. M. F. generated to effect the return of the car to the landing. This is true also in systems wherein the leveling apparatus is omitted, such as 40 those in which the stopping operation is automatic and which are arranged for inching the car back to the floor in the event that it has run past and those in which the starting, stopping and reversal of the car is under manual control. Furthermore, the reversal of the

generator E. M. F. is advantageous for effecting a reversal in the direction of movement of the car at any point in the hatchway. Considerable time may be lost in effecting the reversal of the generator E. M. F., however, due to 55 the time constant of the generator field.

One feature of the present invention resides in minimizing the time required to bring the generator E. M. F. from a certain value of one polarity to a certain value of the other 60 polarity.

Other features and advantages will become apparent from the following description and appended claims.

The invention will be described, by way of 65 illustration, as embodied in a system in which both the starting and stopping of the car is under the control of an operator. It is to be understood, however, that it is also applicable to other elevator systems, such as those 70 in which push button control is employed for causing both the starting and stopping of the car or for causing only the stopping of the car, or those in which the starting of the car is under the control of an operator while the slow down and stopping is automatic. Furthermore, the system in which the invention is embodied will be described, also by way of 75 illustration, as provided with self-leveling mechanism, with the invention applied to the leveling operations. It is to be further understood, however, that the invention is adapted for use in other operations, such as the operation of reversing the car at any point and is applicable to systems in which self-leveling 80 apparatus is not employed, such as those in which the accuracy of the stop is made dependent upon the skill of the operator and in which, in the event of an overrun, the return to the floor is caused by inching, or to 85 those in which the car is caused to stop automatically at the landing and in which means are provided for inching the car back to the floor in the event of an overrun.

The invention involves the polarity of one 90 portion of the generator separately excited field winding being reversed with respect to that of another portion. This causes the magnetizing forces of these portions to act in opposition. Then by varying the magnetizing 95 100

force of either or each of said portions, the net magnetizing force of the winding may be caused to be such that an E. M. F. of either polarity may be obtained, the particular polarity depending upon which one of said portions predominates.

In carrying out the invention, according to the preferred arrangement, certain connections in the generator separately excited field winding circuit are changed for the leveling operation so as to cause the current in a portion of the field winding to flow in a reversed direction with the direction of the flow of current through the remainder of the winding remaining the same. Upon an underrun, the current flowing through said portion is caused to be less than that flowing through the remainder of the winding with the result that an E. M. F. of proper polarity is generated. Upon an overrun, in order to reverse the polarity of the E. M. F. generated so as to effect the return of the car to the landing, the direction of the flow of current through the whole winding is not reversed but the current flowing through said portion is caused to be greater than that flowing through the remainder of the winding.

Other conditions arise, where a variable voltage direct current generator is employed to supply power to the elevator motor, which tend to cause variations in operation during the leveling period. During this period, the generator is required to operate at low values of E. M. F. in order to obtain satisfactory operation for bringing the car to a level with a landing. Due to the residual flux of the generator field, assuming the generator separately excited field winding connected the same for leveling as for operation between floors, the E. M. F. values obtained for a given value of field current during the leveling period vary considerably, depending on the magnetic state of the machine prior to leveling and whether the car is being brought to the landing upon an underrun or returned to the landing after an overrun. Such variations in E. M. F. values cause undesirable variations in the operation of the car during the leveling period. The preferred arrangement of the invention also obviates the effects of the residual flux of the generator and thereby causes more uniform operation during the leveling period.

A system of control directed to similar subject matter is shown in this inventor's copending application, Serial No. 60,769, filed October 6, 1925, and division thereof, Serial No. 273,290, filed April 27, 1928.

In the drawings:

Figure 1 is a diagram of an elevator control system embodying the invention;

Figure 2 is a fragmental schematic view of a portion of the elevator system, illustrating particularly the manner in which the gen-

erator field winding is controlled during the leveling operation; and

Figure 3 is a hysteresis curve employed to illustrate the invention.

No attempt is made in Figure 1 to show the coils and contacts of the various electromagnetic switches in their associated positions, a "straight" diagram being employed wherein the coils and contacts of the various switches are separated in such manner as to render the circuits involved relatively simple. Also the parts of other switches and apparatus are separated in the interest of simplifying the diagram. For a clearer understanding of the invention, the stationary contacts of the switches are illustrated in cross section.

The motor generator set comprises a driving motor 11, illustrated for convenience of description as of the direct current type, and a variable voltage direct current generator 12. The armature of the driving motor is designated 13 and its field winding 14. The armature of the generator is designated 15, its series field winding 16, its separately excited field winding being divided into two portions 17 and 18. The elevator motor is designated as a whole by the numeral 20, its armature being designated 21 and its field winding 22. An adjustable resistance 23 is arranged in shunt to the generator series field winding. Discharge resistances 24 and 25 are provided for the portions 17 and 18 respectively of the generator separately excited field winding. Discharge resistance 26 is provided for the elevator motor field winding. A resistance 27 is provided for controlling the strength of the generator field and therefore the voltage applied to the elevator motor armature. A resistance 28 is provided for controlling the relative values of the current supplied to the generator field winding portions 17 and 18 during leveling. 30 is the release coil for the elevator motor electromagnetic brake. This coil is provided with discharge resistance 31 for controlling the application of the brake during the stopping operation. 32 and 33 are the up slow speed contacts and the down slow speed contacts respectively of the leveling switch, the up and down fast speed leveling switch contacts being designated 34 and 35 respectively. 36 is the armature and 37 is the field winding of the motor 38 for moving the rollers of the leveling switch into position to clear the leveling cams. 40 and 41 are the direct current supply mains. 42 is a double pole knife switch for connecting the system to the supply mains. In order to suit the type of diagram employed, the blades of this switch are shown separated. The car switch is designated as a whole by the numeral 43. 44 is the safety switch in the car. The various safety, limit, stop and emergency switches and door and gate contacts are omitted in order to simplify the description.

The electromagnetic switches have been designated as follows:

A—potential switch,
 B—up direction switch,
 C—down direction switch,
 F—accelerating switch,
 G—maintaining relay,
 H—brake switch,
 L—field control switch,
 M—series field relay,
 N—series field switch,
 P—leveling switch motor relay,
 LU—up leveling direction switch,
 LD—down leveling direction switch,
 LR—field control leveling relay,
 LF—fast speed leveling relay,
 LI—intermediate speed leveling relay.

Throughout the description which follows, these letters, in addition to the usual reference numerals, will be applied to the parts of the above enumerated switches. For example, contacts B 66 are contacts on the up direction switch, while actuating coil A 45 is the coil that operates the potential switch. The electromagnetic switches are shown in their deenergized positions. Inductance coils are similarly designated by the character X.

Upon the closing of the knife switch 42, the driving motor 11, elevator motor field winding 22 and potential switch actuating coil A 45 are energized, the circuit for coil A 45 being by way of line 46 including safety switch 44. The driving motor starts in operation, bringing the generator 12 up to full speed. Starting means for the driving motor are omitted to simplify the description. The potential switch, upon operation, causes the engagement of contacts A 50 and A 51 preparing the circuits for the generator separately excited field winding and the electromagnetic brake release coil and also the control circuits. The condition of the circuits so far described might be termed normal.

Assume that the system is designed for an installation of several floors and that the car is at rest at the first floor landing. In order to start the car in the up direction, the operator moves the car switch into position where its contact bar 52 bridges contacts 53, 54, 55 and 56. Upon the contact bar 52 engaging contact 54, a circuit is completed for the actuation coil B 57 of the up direction switch and the actuating coil H 58 of the brake switch. This circuit may be traced from the left-hand blade of switch 42, by way of line 79 through contacts A 50, by way of line 60 through coils H 58 and B 57, contacts 54 and 53 of the car switch, by way of line 61 through contacts C 62, line 63, switch 44, line 46, by way of line 89, to the right-hand blade of switch 42. The engagement of the contact bar 52 and contact 55 prepares a circuit for the actuating coil F 83 of the accelerating switch. The engagement of the

contact bar 52 and contact 56 completes a circuit for the actuating coil P 59 of the leveling switch motor relay. This circuit may be traced from the left-hand blade of switch 42, by way of line 79 through contacts A 50, by way of line 92 through coil P 59, contacts 56 and 53 of the car switch, to the right-hand blade of switch 42 as above traced.

It is preferred to provide the direction switches with a mechanical interlock to prevent their simultaneous operation. Such an interlock may be of the form of a walking beam pivotally mounted for engaging catches on the armatures of the direction switches. Upon operation of the up direction switch in response to the energization of its actuating coil B 57, contacts B 65 separate and contacts B 66, B 67 and B 68 engage. The separation of contacts B 65 breaks the circuit leading from the car switch down feed contact 70, contacts B 65 and the corresponding down direction switch contacts C 62 serving as electrical interlocks. The engagement of contacts B 68 prepares the circuit for the up direction switch holding coil B 71 and the brake switch holding coil H 72. The engagement of contacts B 66 and B 67 completes a circuit for the generator separately excited field winding. This circuit may be traced from the left-hand blade of switch 42, by way of line 79 through contacts A 50 and resistance 27, by way of line 73 through contacts B 66, by way of line 74, through field control switch contacts L 120, field winding portion 18, by way of line 121 through contacts L 122, field winding portion 17 and actuating coil G 75 of the maintaining relay, by way of line 89 through contacts B 67 and contacts A 51, to the right-hand blade of switch 42. Relay G does not operate at this time as insufficient current is supplied to its actuating coil.

The brake switch H operates simultaneously with the direction switch B. Switch H, upon operation, causes the separation of contacts H 77 and the engagement of contacts H 80 and H 81. The separation of contacts H 77 disconnects the generator separately excited field winding from the generator armature. The purpose of contacts H 77 will be seen from later description. The engagement of contacts H 80 completes the circuit for the brake release coil 30. This circuit may be traced from the left-hand blade of switch 42, by way of line 79 through contacts A 50, by way of line 82 through coil 30 and contacts H 80, by way of line 89 through contacts A 51, to the right-hand blade of switch 42. The engagement of contacts H 81 completes the circuit for the accelerating switch actuating coil F 83. This circuit may be traced from the left-hand blade of switch 42, by way of line 79 through contacts A 50, by way of line 84 through contacts H 81, contacts L 47, inductance coil X 85 and coil F 83,

contacts 55 and 53 of the car switch, by way of line 61 through contacts C 62, line 63, switch 44, line 46, line 89, to the right-hand blade of switch 42.

The leveling switch motor relay, upon operation, causes the engagement of contacts P 93, completing the circuit for the leveling switch motor 38. This circuit may be traced from the left-hand blade of switch 42, by way of line 79 through contacts A 50, by way of line 94 through armature 36 and field winding 37 of motor 38 and contacts P 93, by way of line 89 through contacts A 51, to the right-hand blade of switch 42. The leveling switch motor acts to move the leveling switch operating rollers so as to clear the leveling cams during the movement of the car. This operation will be explained later.

The brake release coil 30 being energized and current being supplied from the generator armature 15 to the elevator motor armature 21, due to the generator field winding portions 17 and 18 being energized, the elevator motor starts. The field winding portions 17 and 18 as now connected assist each other.

The accelerating switch F does not operate immediately the circuit for its actuating coil F 83 is completed, its action being delayed by the inductance coil X 85. Upon operation, switch F causes the separation of contacts F 87 and the engagement of contacts F 88 and F 90. The separation of contacts F 87 removes the short-circuit around the holding coil P 91 of the leveling switch motor relay. The engagement of contacts F 88 completes the circuit for holding coils B 71, P 91 and H 72. This circuit may be traced from the left-hand blade of switch 42, by way of line 79 through contacts A 50, by way of line 95 through coil B 71 and contacts B 68, by way of line 96 through coils P 91 and H 72 and contacts F 88, by way of line 89 through contacts A 51, to the right-hand blade of switch 42. The purpose of the energization of these holding coils will be seen from later description. The engagement of contacts F 90 short-circuits resistance 27, increasing the voltage applied to generator field winding portions 17 and 18. Thus the generator voltage is brought up to its full value and the motor comes up to full speed. Also sufficient current is now supplied to the coil G 75 to cause the operation of the maintaining relay. Thus contacts G 97 engage, by-passing accelerating switch contacts F 88. It is to be understood that several accelerating switches may be employed to short-circuit successively sections of resistance 27, all but one, illustrated as short-circuiting the whole of the resistance, being omitted in order to simplify the description.

The starting of the car in the down direction is accomplished in a similar manner and

will be only briefly described. The operator moves the car switch into position where its contact bar 52 bridges contacts 70, 98, 100 and 101. Upon the engagement of the contact bar and contact 98, a circuit is completed for the down direction switch actuating coil C 102 and coil H 58 which circuit may be traced from the left-hand blade of switch 42, through coil H 58, as previously traced, by way of line 103 through coil C 102, car switch contacts 98 and 70, by way of line 63 through contacts B 65, to the right-hand blade of switch 42 as previously traced. The engagement of the contact bar and contact 100 prepares a circuit for coil F 83 and the engagement of the contact bar and contact 101 completes a circuit for the coil P 59 by way of line 104. The down direction switch, upon operation, causes the separation of contacts C 62 and the engagement of contacts C 105, C 106 and C 107, these contacts corresponding with up direction switch contacts B 65, B 66, B 67 and B 68 respectively. The holding coil of the down direction switch is designated C 64. The circuit for coil F 83 is completed by contacts H 81 as before. Further than this, the operation of starting the car in the down direction is the same as described for starting it in the up direction.

Assume that the car is running in the up direction and that the operator centers the car switch between the second and third floors in order to stop at the third floor landing. Upon the disengagement of the contact bar 52 and contact 56, the circuit for the leveling switch motor relay actuating coil P 59 is broken. The relay remains in operated condition, however, due to its holding coil P 91. The disengagement of contact 55 and the contact bar breaks the circuit for the accelerating switch actuating coil F 83. The accelerating switch, therefore, drops out, causing the separation of contacts F 88 and F 90 and the engagement of contacts F 87. The separation of contacts F 88 is simply in preparation for the next starting operation, the circuit for coils B 71, P 91 and H 72 being maintained by contacts G 97. The separation of contacts F 90 removes the short-circuit for resistance 27, decreasing the strength of the generator field winding portions 17 and 18. Thus the generator E. M. F. is decreased and the speed of the elevator motor is reduced. Discharge resistances 24 and 25 act to smooth out the retardation. The engagement of contacts F 87 short-circuits the holding coil P 91 of the leveling switch motor relay. The disengagement of contact 54 and contact bar 52 breaks the circuit for actuating coils B 57 and H 58. The up direction switch and brake switch are maintained in operated condition, however, by their holding coils B 71 and H 72 respectively.

The leveling switch motor relay P, dropping out upon the short-circuiting of coil

P 91, causes the separation of contacts P 93 to deenergize the leveling switch motor 38. In this manner the operating rollers of the leveling switch are extended for engagement by the leveling cams. Referring to Figure 2, the leveling switch motor is operatively connected to the leveling switch by means of an arm 108 on the motor shaft, a connecting link 110 and a lever 111. In the starting operation, the motor 38 being energized, arm 108 rotates, acting through link 110 and lever 111 to move the leveling switch as a whole about a pivot. In this manner the leveling switch operating rollers 112 and 113 are moved into position where they do not engage the leveling cams 114 and 115 during motion of the car, a stop being provided to determine the extent of the movement. It is to be understood that leveling cams are provided for each floor. The leveling switch is pivoted on a bracket 116 secured to the car frame. In the stopping operation, upon the deenergization of the leveling switch motor, a spring (not shown) moves the lever 111 and therefore the leveling switch back into the first described position with the rollers 112 and 113 extended for engagement by the leveling cams. Each pair of leveling contacts 32, 33, 34 and 35 comprises a stationary contact and a movable contact operated by the engagement of its corresponding roller and leveling cam. The fast speed contacts 34 and 35 are arranged to separate before their corresponding slow speed contacts 32 and 33 in the leveling operation. Springs (now shown) are provided for causing the separation of the contacts of the pairs as the leveling operation is effected and stops are provided for determining the extent of movement of the rollers as they ride off the leveling cams.

It will be assumed that the car has not reached the landing and that the up leveling switch operating roller 112 moves onto the vertical surface of up leveling cam 114 before relay G drops out. Referring to Figure 1 and also to Figure 2 where portions of the circuits employed for leveling are illustrated and where the coils and contacts of the particular switches included are illustrated in their proper associated relations, the engagement of leveling switch up slow speed contacts 32 completes a circuit for the up leveling direction switch actuating coil LU 78 and the field control leveling relay actuating coil LR 117. This circuit may be traced from the left-hand blade of switch 42, by way of line 79 through contacts A 50, line 124, leveling switch contacts 32, by way of line 125 through coil LU 78 and coil LR 117, by way of line 89 through contacts A 51, to the right-hand blade of switch 42. The engagement of the leveling switch up fast speed contacts 34 completes the circuit for fast speed leveling relay actuating coil LF 130. This circuit

may be traced from the left-hand blade of switch 42, by way of line 79 through contacts A 50, line 124, leveling switch contacts 32, by way of line 131 through leveling switch contacts 34, by way of line 132 through coil LF 130 and resistance 133, to the right-hand blade of switch 42 as previously traced. It is to be noted that, due to the fact that the circuit for coil LF 130 is through leveling switch slow speed contacts 32, the circuit for coils LU 78 and LR 117 must be made in order that the circuit for coil LF 130 may be completed.

The field control leveling relay LR, upon operation, causes the engagement of contacts LR 127, LR 134 and LR 135. The engagement of contacts LR 127 completes a discharge circuit around the actuating coil of the relay, the circuit including discharge resistance 162 and inductance coil X 126. The engagement of contacts LR 134 completes a circuit for the up direction switch and brake switch actuating coils B 57 and H 58 respectively, causing their reenergization. This circuit may be traced from the left-hand blade of switch 42, by way of line 79 through contacts A 50, by way of line 60 through coil H 58, coil B 57 and contacts LR 134, by way of line 89 through contacts A 51, to the right-hand blade of switch 42. The reenergization of these coils has no particular effect under the assumed sequence of operation of the switches, however, as the up direction switch and brake switch are being maintained in operated condition by holding coils B 71 and H 72. The engagement of contacts LR 135 completes the circuit for the actuating coil L 136 of the field control switch. This circuit may be traced from the left-hand blade of switch 42, by way of line 79 through contacts A 50, by way of line 137 through contacts LR 135 and coil L 136, by way of line 89 through contacts A 51, to the right-hand blade of switch 42.

The field control switch L, upon operation, causes the separation of contacts L 47, L 120 and L 122 and the engagement of contacts L 140, L 141 and L 142. The purpose of contacts L 47 and L 142 will be seen from later description. The separation of contacts L 120 and L 122 breaks the circuit for portions 17 and 18 of the generator separately excited field winding. The immediate engagement of contacts L 140 and L 141, however, reconnects these portions to the mains. The polarity of the latter connection is such that the direction of the flow of current through portion 18 is reversed while the direction of the flow of current through winding portion 17 remains the same. As a result of this change of connections, the magnetizing force due to winding portion 18 opposes that due to winding portion 17. As above set forth, however, actuating coil LU 78 of the up leveling direction switch was energized upon the en-

gagement of the leveling switch slow speed contacts 32. This switch, operating along with relay LR, causes the engagement of contacts LU 144. Thus, as the field control switch operates to reverse the connections for field winding portion 18, switch LU operates through its contacts LU 144 to connect a portion of resistance 28 in parallel with this winding portion so that the current in portion 18 is less than that in portion 17. The magnetizing force due to portion 18, therefore, is less than that due to portion 17.

As previously set forth, fast speed leveling relay actuating coil LF 130 was energized by the engagement of up fast speed leveling contacts 34. This relay, upon operation, causes the separation of contacts LF 145 and the engagement of contacts LF 146. The purpose of contacts LF 145 will be explained later. The engagement of contacts LF 146 short-circuits a portion of resistance 28. Thus, under the assumed sequence of operations, the fast speed leveling relay is effective to determine the amount of resistance 28 which is connected across field winding portion 18 by the engagement of contacts LU 144, this amount of resistance being indicated as adjustable section 147.

The engagement of field control switch contacts L 142 short-circuits a portion of resistance 27 for the generator separately excited field winding, the amount of resistance in this portion being adjusted to give satisfactory operation for the particular installation. With contacts L 120 and L 122 separated and contacts B 66, B 67, L 140, L 141, L 142, LU 144 and LF 146 in engagement, an E. M. F. is generated which causes the elevator motor to run at a suitable fast leveling speed in the up direction as will be seen from later description.

Discharge resistances 24 and 25 act to smooth out not only the change in generator E. M. F. due to the reinsertion of resistance 27 in circuit with the field winding but also that due to the above described change in connections for effecting the leveling operation.

It is to be noted that the separation of contacts L 120 and L 122 also breaks the circuit for the actuating coil G 75 of the maintaining relay. Relay G, therefore, dropped out to separate contacts G 97, breaking the circuit for holding coils B 71 and H 72 of the up direction switch and the brake switch respectively. These switches were maintained in operated condition, however, by their actuating coils, the engagement of contacts LR 134 causing the reenergization of these coils as previously explained. Relay G is maintained operated after contacts F 90 separate to remove the short-circuit for resistance 27 because of the fact that the current through its actuating coil is sustained by the action of field winding portion 17 and discharge re-

sistance 24. Thus, even though switch L has not operated to cause the separation of contacts L 120 and L 122, should the current in the maintaining relay actuating coil G 75 decrease to a predetermined value, the relay would drop out. Such operation might result from too early centering of the car switch, i. e., the current in coil G 75 would decrease to this predetermined value before the operation of the leveling switch to cause the engagement of its slow speed contacts. As a result, contacts G 97 would separate to deenergize the up direction switch and brake switch holding coils B 71 and H 72 respectively. This might permit the direction switch and brake switch to drop out, their actuating coils having been deenergized by the centering of the car switch. The engagement of the slow speed leveling contacts 32, however, as roller 112 rode onto the vertical surface of its leveling cam, would cause the engagement of contacts LR 134 and thus the energization of coils B 57 and H 58.

The up leveling direction switch LU, upon operation, also caused the engagement of contacts LU 170 and LU 171. The purpose of contacts LU 170 will be seen from later description. The engagement of contacts LU 171 completed the circuit for actuating coil M 123 of the series field relay. This circuit may be traced from the left-hand blade of switch 42, by way of line 79 through contacts A 50, by way of line 172 through contacts LU 171, inductance coil X 150 and coil M 123, by way of line 89 through contacts A 51, to the right-hand blade of switch 42. The series field relay M did not operate immediately upon the completion of the circuit for its actuating coil, its action being delayed by the effect of inductance coil X 150. Relay M, upon operation, causes the engagement of contacts M 151 to complete the circuit for the series field switch actuating coil N 152. This circuit may be traced from the left-hand blade of switch 42, by way of line 79 through contacts A 50, by way of line 153 through coil N 152 and contacts M 151, by way of line 89 through contacts A 51, to the right-hand blade of switch 42. Switch N, upon operation, causes the separation of contacts N 154, breaking the circuit including resistance 23 in shunt to the generator series field winding 16. The generator series field coils are so wound that, without the parallel resistance 23, they would have too great an effect for proper operation of the car. The desired compounding is obtained by employing the low resistance shunt. Upon separation of contacts N 154, the strength of the series field is increased for the leveling operation so as to aid in obtaining the desired stopping operation. The short delay in the action of relay M, and therefore the switch N, upon the initiation of the leveling operation, is desirable in order that the current in the gen- 130

erator armature-elevator motor armature circuit may adjust itself to such a value that proper series field strength during the leveling operation may be obtained.

As the car nears the third floor landing, roller 112 rides off the vertical surface onto the oblique surface of cam 114. This results in the separation of up fast speed leveling contacts 34, deenergizing actuating coil LF 130 of the fast speed leveling relay. The fast speed leveling relay, upon dropping out, causes the separation of contacts LF 146 and the engagement of contacts LF 145. The separation of contacts LF 146 removes the short-circuit for section 155 of resistance 28, increasing the ohmic value of the resistance shunting generator field winding portion 18. Thus the current now supplied to field winding portion 18 is increased and that supplied to winding portion 17 is decreased. The generator E. M. F., therefore, is again lowered and the elevator motor runs at an intermediate leveling speed. The separation of contacts LF 145, upon the operation of the fast speed leveling relay, prevented the energization of the intermediate speed leveling relay actuating coil LI 156 upon the engagement of up leveling direction switch contacts LU 170. Upon the dropping out of the fast speed relay, however, the reengagement of contacts LF 145, completes the circuit for coil LI 156. This circuit may be traced from the left-hand blade of switch 42, by way of line 79 through contacts A 50, by way of line 157 through contacts LU 170, inductance coil X 158, coil LI 156 and contacts LF 145, by way of line 89 through contacts A 51, to the right-hand blade of switch 42. The relay LI does not operate immediately, however, its action being delayed by the effect of inductance coil X 158. It is to be noted that, if the leveling operation is such that the up fast speed leveling contacts 34 do not engage and therefore the fast speed leveling relay actuating coil is not energized to cause the separation of contacts LF 145, the inductance coil X 158 acts to delay the operation of relay LI upon the engagement of contacts LU 170. The relay LI, upon operation, causes the separation of contacts LI 160 to remove the short-circuit for the remaining section 161 of resistance 28, again increasing the ohmic value of the resistance shunting generator field winding portion 18. Thus the current supplied to field winding portion 18 is increased and that supplied to winding portion 17 is decreased. The generator E. M. F., therefore, is still further decreased and the elevator motor runs at its slowest speed.

Shortly before the car reaches an exact level with the landing, the roller 112 rides off the oblique surface of cam 114, thereby separating the slow speed leveling contacts 32. The circuit for coil LU 78 and coil LR

117 is thus broken. The up leveling direction switch LU drops out immediately, separating contacts LU 144, LU 170 and LU 171. The separation of contacts LU 171 breaks the circuit for coil M 123, relay M dropping out to cause the separation of contacts M 151, breaking the circuit for series field switch coil N 152. Switch N, therefore, drops out to cause the reengagement of its contacts N 154 to reconnect resistance 23 in shunt to the generator series field winding. The separation of contacts LU 144 disconnects resistance 28 from across field winding portion 18, thereby rendering the opposing magnetizing forces exerted by winding portions 17 and 18 equal. As will be seen as the description proceeds, however, switches B, L and H operate, as soon as relay LR drops out, to disconnect the winding portions from the mains and to reconnect them for cumulative action to the generator armature.

Relay LR does not drop out immediately the circuit for its actuating coil LR 117 is broken, its action being delayed by the effect of inductance coil X 126 and discharge resistance 162. The purpose of the delay in the dropping out of relay LR will be seen from later description treating with the operation of the system during an overrun. Relay LR, upon dropping out, causes the separation of contacts LR 127, LR 134 and LR 135. The separation of contacts LR 127 breaks the circuit comprising resistance 162 and inductance coil X 126 in shunt to coil LR 117. The separation of contacts LR 134 breaks the circuit for coils H 58 and B 57. The separation of contacts LR 135 breaks the circuit for coil L 136.

Upon the circuit for its actuating coil 105 being broken, up direction switch B drops out, causing the separation of contacts B 66, B 67 and B 68 and the reengagement of contacts B 65. Switch H drops out along with switch B, causing the separation of contacts 110 H 80 and H 81 and the reengagement of contacts H 77. Switch L, upon dropping out, causes the separation of contacts L 140, L 141 and L 142 and the engagement of contacts 115 L 47, L 120 and L 122. The separation of contacts B 68 opens line 95 including holding coil B 71, the circuit for coil B 71 and coil H 72 having already been broken, however, by the separation of contacts G 97 as previously described. The engagement of contacts B 65 completes the circuit leading from 120 the car switch down feed contact 70. The separation of contacts H 81 opens line 84 including coil F 83, the circuit for this coil having been previously broken by the centering of the car switch. Contacts L 47 will be referred to later. The separation of contacts L 142 removes the shunt around the portion of resistance 27, short-circuited to obtain the desired leveling operation. The 125 130

separation of contacts L 140 and L 141 and the engagement of contacts L 120 and L 122 reconnects the field winding portions for cumulative action, the field winding being simultaneously disconnected from the mains and connected to the generator armature, however, by the separation of contacts B 66 and B 67 and the engagement of contacts H 77. The separation of contacts H 80 breaks the circuit for the brake release coil 30, effecting the application of the brake. The polarity of the connection of the generator field winding to the generator armature is such that the generator sends current through the whole winding in a direction to oppose the flux which produces the generator E. M. F., thus tending to destroy the residual flux of the generator field.

Thus, the brake being applied and the generator separately excited field winding being disconnected from mains 40-41, the car is brought to rest level with the third floor landing.

In the event of an overrun, assuming in the above example that the car overruns the third floor to the extent of causing the engagement of down slow speed leveling contacts 33, a circuit is completed for coil LR 117 and actuating coil LD 165 of the down leveling direction switch. This circuit may be traced from the left-hand blade of switch 42, by way of line 79 through contacts A 50, line 124, contacts 33, by way of line 166 through coil LD 165, by way of line 125 through coil LR 117, by way of line 89 through contacts A 51, to the right-hand blade of switch 42. The down leveling direction switch LD, upon operation, causes the engagement of contacts LD 175, LD 176 and LD 177. As previously explained, relay LR is maintained operated after up slow speed leveling switch contacts 32 separate by the action of inductance coil X 126 and discharge resistance 162. This portion of the system is adjusted so as to maintain relay LR operated during an overrun until the circuit for its actuating coil LR 117 is completed by the engagement of the slow speed leveling switch contacts for returning the car to the floor, these contacts being down slow speed leveling switch contacts 33 in the example assumed. Thus, upon an overrun into a slow speed leveling zone, contacts LR 134 and LR 135 remain in engagement maintaining the brake switch H, up direction switch B and field control switch L operated. The engagement of down leveling direction switch contacts LD 175, therefore, connects a portion of resistance 28 across field winding portion 17 so that the current in winding portion 17 is now less than that in winding portion 18. Throughout the leveling operations described for bringing the car to the floor during an underrun, the current supplied to winding portion 18 from the mains was in a direction

such as to tend to cause the generation of an E. M. F. of a polarity for causing the motor to move the car in the opposite direction, namely, downwardly. The current supplied to winding portion 17, however, was in the same direction as was previously supplied to the whole winding before the leveling mechanism took control, thus tending to cause the generation of an E. M. F. of a polarity for causing the motor to continue to move the car in the same direction. Due to the fact that winding portion 18 was shunted during this operation by varying portions of resistance 28, the magnetizing force of winding portion 17 predominated and the E. M. F. generated was of proper polarity for causing the car to continue upwardly toward the third floor landing. Upon an overrun, the current through the field winding portions is not reversed due to the operation of the leveling mechanism to effect the return of the car to the floor, the direction of the current supplied to winding portion 17 remaining in the direction tending to cause the generation of an E. M. F. of a polarity for causing the motor to move the car in the same direction (upwardly) and the direction of the current supplied to winding portion 18 remaining in a direction tending to cause the generation of an E. M. F. of a polarity for causing the motor to move the car in the opposite direction (downwardly). As the engagement of contacts LD 175 places the desired portion of resistance 28 in shunt to winding portion 17, however, the magnetizing force due to winding portion 18 predominates, causing the generation of an E. M. F. of proper polarity for causing the elevator motor to start the car in the down direction to return to the floor. As intermediate speed leveling relay contacts LI 160 are in engagement short-circuited section 161 of resistance 28 and as the operation of the relay to separate these contacts, upon the energization of its actuating coil LI 156 by the engagement of contacts LD 176, is delayed by the effect of inductance coil X 158, the generation of sufficient voltage to cause the elevator motor to start the car upon its return movement to the landing is assured.

The engagement of contacts LD 177, arranged in parallel with up leveling direction switch contacts LU 171, completes the circuit for series field relay actuating coil M 123. As before, the operation of relay M is delayed by the effect of inductance coil X 150. Thus contacts N 154, depending for their separation upon the operation of relay M, remain closed momentarily to insure that the current in the generator armature-motor armature circuit has fallen to a low value. Since the current in the series field winding may be flowing in a direction such as to cause the generation of an E. M. F. which is of proper

5 polarity for operating the car in the down direction, immediate increase in the strength of the series field might result in the car again being carried past the floor. As the car returns to the floor, it is stopped by the separation of slow speed leveling contacts 33 in a manner similar to that described for approaching the floor in the up direction.

If the overrun is great enough to cause the engagement of the leveling switch down fast speed contacts 35 as well as the leveling switch down slow speed contacts 33, coil LF 130 is energized. As before, relay LF causes the engagements of contacts LF 146 to short-circuit sections 155 and 161 of resistance 28, increasing the generator voltage and causing the elevator motor to run at its fast leveling speed. Also contacts LF 145 separate to prevent the energization of intermediate speed leveling relay actuating coil LI 156 by the engagement of contacts LD 176. Further than this, the operation on an overrun is as above described.

The operation of the system is somewhat modified in the event that a stop is to be made when the car is moving downwardly. In order to briefly describe the operation, assume that the stopping operation has progressed to the extent that the leveling switch operating rollers have been extended for engagement by the leveling cams and that down roller 113 moves onto the vertical surface of down cam 115 before relay G drops out. The engagement of the leveling switch down slow speed contacts 33 completes the circuit, previously traced, for down leveling direction switch coil LD 165 and field control leveling relay coil LR 117. Relay LR causes the engagement of contacts LR 134 completing the circuit for up direction switch actuating coil B 57 and brake switch actuating coil H 58 and the engagement of contacts LR 135 completing the circuit for the field control switch coil L 136, these circuits having been previously traced. The energization of coil H 58 is to maintain switch H operated upon the deenergization of its holding coil H 72. Down direction switch C being maintained in operated condition by its holding coil C 64, the direction switch mechanical interlock acts to prevent the operation of the up direction switch B in response to the energization of coil B 57 until the down direction switch drops out. Switch L, as before, operates to reverse the connections for field winding portion 18, the separation of contacts L 120 and L 122 breaking the circuit for coil G 75 of the maintaining relay. Relay G, therefore, drops out, separating its contacts G 97 to break the circuit for the holding coils H 72 and C 64. The down direction switch C, therefore, drops out to separate contacts C 105 and C 106 and the up direction switch B operates to cause the engagement of contacts B 66 and B 67.

Thus the connection for the whole field winding is reversed so that the net result of the operation of switches L, C and B is that the direction of the flow of current through winding portion 17 is reversed while the flow of current through winding portion 18 remains the same. Thus the magnetizing force due to winding portion 17 opposes that due to winding portion 18. As set forth above, however, actuating coil LD 165 of the down leveling direction switch was energized upon the engagement of the leveling switch slow speed contacts 33. This switch, operating along with relay LR, causes the engagement of contacts LD 175. Thus, as the field control switch and main direction switches operate to reverse the connections for field winding portion 17, switch LD operates to connect resistance 28 in parallel with this winding portion so that the current in portion 17 is less than that in portion 18. Thus the magnetizing force due to portion 17 is less than that due to portion 18.

The engagement of the down fast speed leveling contacts 35, along with the slow speed contacts 33, causes the operation of the fast speed leveling relay. As previously explained, the fast speed leveling relay, by means of its contacts LF 146, causes all of resistance 28 except section 147 to be short-circuited. Also field control switch contacts L 142 short-circuit the selected portion of resistance 27. As in the case where the car was brought to the landing upon an under-run in the up direction, with contacts L 120 and L 122 separated and contacts B 66, B 67, L 140, L 141, L 142, LD 175 and LF 146 in engagement, an E. M. F. is generated which causes the elevator motor to run at a suitable fast leveling speed in the down direction.

It is believed that the remainder of the operation of bringing the car to the landing will be obvious from the description of bringing it to the landing upon an underrun when moving in the up direction. Should the car be carried past the landing, when moving in the down direction, resistance 28 is connected in parallel with field winding portion 18, causing the car to be returned to the landing. 110 15

It is to be understood that the operator may control both the acceleration and retardation of the car by moving the car switch in steps. Should the operator suddenly move the car switch from one position into the other, for example from up into down position, injury to the system is prevented by contacts B 65 which remain separated until the up direction switch drops out. Field control switch contacts L 47, arranged in the circuit for the actuating coil F 83 of the accelerating switch, prevent the operation of the accelerating switch during the leveling period. 120 125

During the leveling period, in systems such 130

as those in which the generator separately excited field winding is connected to the source in the same manner during leveling as during car switch operation with the desired low values of generator E. M. F. for leveling obtained by permitting only a small amount of current to flow through the winding, were the same values of current supplied to the winding for bringing the car to the floor upon an underrun as for returning the car to the floor after an overrun, variations in operation might occur due to the varying effects of the residual flux of the generator field. As such small values of current effect the production of low values of flux, the residual flux present would form a large percentage of the total flux and therefore might affect the operation of the system very markedly. In order that the effects of the residual flux may be clearly seen, reference may be had to the assumed hysteresis curve shown in Figure 3. This figure illustrates the conditions when a small current is supplied to the separately excited field winding of a generator, as during the leveling operation. The magnetizing forces due to this small current are represented as NI and $-NI$, depending on whether the car is approaching the floor, or returning to the floor after an overrun. Assume that the generator armature E. M. F. has been of a value V_1 and that later, in attempting to make a landing, the self-leveling operation takes place with the car approaching the floor. The E. M. F. of the generator during this period will be of a value V_2 . On the other hand, if the car overruns the floor, the E. M. F. of the generator for returning the car to the floor will be of a value V_3 , which value is much less than the value V_2 . Hence the speed of the elevator motor is much less. The values V_2 and V_3 of the generator E. M. F. may vary during operation of the system depending upon the previous magnetic state of the machine. Obviously, such differences in the numerical values of the E. M. F. generated would result in undesirable variations in operation under leveling conditions. These variations cannot be satisfactorily corrected merely by adjusting the amount of resistance in series with the separately excited field winding. For example, if the amount of resistance were decreased in order to raise the value of V_3 , the value V_2 also would be increased, resulting in an increasing tendency to run past the floor. Similarly, if the amount of resistance were increased in order to lower the value of V_2 , the value of V_3 also would be lowered, which value might be too low to effect the return of the car to the floor after an overrun. If the effects of residual flux are eliminated for leveling operating conditions, the system may be adjusted so as to obtain more uniform operation. This desired result may be attained by reversing the polarity of certain of the field poles. The

preferred arrangement for effecting this change has already been described in connection with Figures 1 and 2, the particular arrangement of the separately excited field winding being illustrated in Figure 2.

Referring to Figure 2, it is preferred to group the coils for the north and south poles N and S together to form the portion 17 and those for the north and south poles N_1 and S_1 together to form the portion 18. The coils forming the portion 17 are connected in series relation as are those forming the portion 18. For convenience of explaining the action of portions 17 and 18 of the field winding, assume again that the car is moving in the up direction. With switch L in deenergized position, as during car switch operation, the current flows through the field coils in such manner as to provide poles of alternate polarity as indicated. Upon an underrun in stopping, the up main direction switch contacts B 66 and B 67 remain in engagement and switch L operates to cause the separation of contacts L 120 and L 122 and the engagement of contacts L 140 and L 141. Thus, as previously described, although the direction of the flow of current through the coils for poles N and S (winding portion 17) is not affected, the current through the coils for poles N_1 and S_1 (winding portion 18) is reversed. Thus N_1 becomes a south pole and S_1 becomes a north pole. Similarly, upon an underrun in stopping, where the car has been moving in the down direction during car switch operation, the down main direction switch drops out and the up main direction switch B and field control switch L operate to cause the separation of contacts L 120 and L 122 and the engagement of contacts B 66, B 67, L 140 and L 141. Thus the net result, as previously explained, is to cause the current to flow in the same direction through the coils for poles N_1 and S_1 (winding portion 18) but to reverse the flow of current through the coils for poles N and S (winding portion 17). Thus N becomes a south pole and S becomes a north pole. If these poles were excited equally with the winding connected for the leveling operation, the value of the total E. M. F. at the generator brushes 19 would be substantially zero, since the voltage generated in part of the generator armature winding would be balanced out by a voltage of equal value but opposite polarity generated in the remainder of the winding. However, as previously explained, a difference in the values of the magnetizing forces due to the winding portions is obtained by connecting resistance 28 in parallel with one of the winding portions so that an E. M. F. at the generator brushes is obtained. By utilizing a large magnetizing force for each pole and by employing a resistance 28 of such ohmic value as will cause a proper difference in the values of these magnetizing forces, an

E. M. F. of low value suitable for the leveling operation may be obtained. The large magnetizing forces may be obtained by short-circuiting a portion of resistance 27 as by contacts L 142 (see Figure 1), the amount of resistance short-circuited being adjustable to suit the requirements of the particular installation. Should an overrun occur, contacts L 142 remain in engagement and the selected portion of resistance 27 remains short-circuited so that large magnetizing forces are still employed for the poles, the generation of an E. M. F. for returning the car to the floor, as previously explained, being obtained by disconnecting resistance 28 from one winding portion and connecting it in parallel with the other. In this manner, the iron of the various parts of the magnetic circuit of the generator field structure is worked on the high portions of the hysteresis loop where the effect of residual flux is practically nil, and E. M. F.'s may be obtained, during leveling operations, the values of which are not affected by residual flux and are practically the same whether the car underruns or overruns the landing.

The series field winding 16 acts to assist the separately excited field winding portions to obtain the desired conditions during operation. Under normal car switch operation, when these winding portions assist each other, the series field winding acts in the usual manner to compensate for varying load conditions. During leveling conditions, when the elevator motor is lifting a load, the effect of the series field winding is to aid in bringing the car to the floor since the current flow in the series field winding is in such direction as to produce a magnetizing force which assists that due to the field winding portion through which the predominating current flows and opposes that due to the field winding portion through which less current flows. Conversely, when the elevator motor is lowering a load, the effect of the series field winding is to aid in causing the car to stop at the floor since the current flow in the series field winding is in such direction as to produce a magnetizing force which opposes that due to the field winding portion through which the predominating current flows and assists that due to the field winding portion through which less current flows.

As previously explained, upon an overrun, the up main direction switch contacts B 66 and B 67 are retained in engagement to maintain the current supplied to the winding portions 17 and 18 built up so that the transfer of resistance 28 from across one winding portion to the other to effect the generation of an E. M. F. for returning the car to the floor simply causes a reapportionment of the amount of current supplied to each winding portion. For convenience of explanation, assume that the car has been moving in the up

direction and that it overruns the desired landing in stopping. During the part of the leveling period that the car is below the floor, resistance 28 is connected in parallel with winding portion 18 causing the current supplied to winding portion 18 to be less than that supplied to winding portion 17. The transfer of resistance 28 causes the current in winding portion 18 to be increased and that in winding portion 17 to be decreased to the extent that current in winding portion 17 becomes less than that in winding portion 18. Thus, considering the generator E. M. F. due to the separately excited field winding, the predominating voltage generated in one portion of the generator armature winding decreases and the opposing voltage generated in the remaining portion of the armature winding increases with the result that the so termed opposing voltage is caused to predominate and an E. M. F. at the generator brushes is obtained for causing the car to be returned to the floor. Due to the fact, however, that the current in one winding portion is simply decreased while that in the other is increased, the change in the values of the opposing magnetizing forces of the winding portions occurs very quickly. Consequently, the change in the relative values of the opposing voltages generated in the generator armature winding portions and therefore the establishment of a generated E. M. F. suitable for returning the car to the floor upon an overrun also occurs quickly. Thus the time required to return the car to the desired landing in the event of an overrun is minimized with the result that the overall operating efficiency of the system as a whole is raised considerably.

It is to be understood that the above described arrangement is suitable for use with various types of generators and that these generators may be of other pole numbers, a four pole generator being chosen merely for convenience of description. It is further to be understood that the portions of the field winding may be arranged in different circuit relations and that the coils may be grouped differently to effect the desired result.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. In combination; an elevator car; a hoisting motor therefor; a generator for supplying current to said motor, said generator having a field winding; a source of current; and means for causing the motor to level the

car with a desired landing in stopping, regardless of whether it underruns or overruns said landing, said means comprising means for connecting said winding to said source in such manner that the E. M. F. generated due to the flux created by the current flowing in a portion of the winding opposes that generated due to the flux created by the current flowing in the remainder of the winding, 5 means for causing the first mentioned flux to be less than the second mentioned flux to cause the generation of a total E. M. F. of proper polarity for bringing the car to the landing during an underrun in one direction and for returning the car to the landing after 10 an overrun in the other direction, and means for causing the second mentioned flux to be less than the first mentioned flux to cause the generation of a total E. M. F. of proper polarity for bringing the car to the landing during 15 an underrun in said other direction and returning the car to the landing after an overrun in said one direction.

2. In combination; an elevator car; a hoisting motor therefor; a generator for supplying current to said motor, said generator having a field winding; a source of current; means for connecting the whole of said winding to said source to cause the generation of an E. M. F. of certain value for causing the motor to move the car between landings; and means for causing the motor to level the car with a desired landing in stopping from one direction, regardless of whether it underruns or overruns the landing, said last named means comprising means for reversing the connections for a portion of said winding, a resistance, and means for connecting said resistance in parallel with the reversed portion of said winding during an underrun and in parallel with the remaining portion of said winding during the return of the car to the landing after an overrun.

3. In combination; an elevator car; a hoisting motor therefor; a generator for supplying current to said motor, said generator having a field winding divided into two portions; a source of current; means for connecting the whole of said winding to said source so as to cause said portions to act cumulatively to obtain a terminal E. M. F. of certain value for causing the motor to move the car between landings; and means for causing the motor to level the car with a desired landing in stopping, regardless of whether it underruns or overruns the landing, said last named means comprising means for reconnecting the whole of said winding to said source so as to cause said portions to act in opposition, a resistance, means for connecting a portion of said resistance in parallel with one of said winding portions to obtain a terminal E. M. F. of a lower value than said certain value and of proper polarity for bringing the car to the landing upon an underrun in one

direction and for returning the car to the landing after an overrun in the other direction and for connecting said portion of said resistance in parallel with the other winding portion to obtain a terminal E. M. F. of a lower value than said certain value and of proper polarity for bringing the car to the landing upon an underrun in said other direction and for returning the car to the landing after an overrun in said one direction, and means for increasing the amount of said resistance so connected, during underruns in either direction and the returning of the car after overruns in either direction, as the car nears the landing.

4. In combination; an elevator car; a hoisting motor therefor; a generator for supplying current to said motor, said generator having a field winding; a source of current; and means for causing said motor to bring the car to a stop at a desired landing, said means comprising means for connecting said winding to said source in such manner that the E. M. F. generated due to the flux created by the current supplied to a portion of said winding opposes the E. M. F. generated due to the flux created by the current supplied to the remainder of said winding, means for causing the first mentioned flux to be less than the second mentioned flux to cause the generation of a total E. M. F. of a certain value to cause the motor to run at a certain speed, and means for increasing the first mentioned flux and for decreasing the second mentioned flux as the car nears the landing to decrease the total E. M. F. and therefore the speed of the motor.

5. In combination; an elevator car; a hoisting motor therefor; a generator for supplying current to said motor, said generator having a field winding; a source of current; means for connecting said winding to said source to cause the motor to run at a certain speed; means for decreasing the speed of said motor, said second named means comprising means for reversing the connections for a portion of said winding, a resistance, and means for connecting a portion of said resistance in parallel with said reversed portion of the winding; and means for further decreasing the speed of said motor, said last named means comprising means for increasing the amount of said resistance so connected.

6. In combination; an elevator car; leveling mechanism for said car, said mechanism comprising fast speed contacts and slow speed contacts; and means responsive to the engagement of said fast speed contacts for causing the car to run at a fast leveling speed and responsive to the separation of said fast speed contacts, with the slow speed contacts in engagement, for causing the car to run at a speed which is intermediate the fast and slow leveling speeds and thereafter, upon the

expiration of a predetermined time interval after the separation of said fast speed contacts, for causing the car to run at slow leveling speed.

7. In combination; an elevator car; a hoisting motor for said car; a source of current for said motor; means adapted to vary the voltage applied to said motor from said source; means for causing said motor to operate the car between landings, said second named means comprising means for controlling said voltage varying means to control the speed of the motor; and means for causing the motor to level the car with a desired landing in stopping, said last named means comprising leveling mechanism having fast speed leveling contacts and slow speed leveling contacts, means responsive to the engagement of the fast speed contacts and the slow speed contacts for controlling said voltage varying means to cause the motor to operate the car at a fast leveling speed and responsive to the separation of the fast speed leveling contacts for controlling said voltage varying means to cause the motor to operate the car at an intermediate leveling speed, and means responsive to the separation of the fast speed contacts and operable upon the expiration of a predetermined time interval thereafter for controlling said voltage varying means to cause the motor to operate the car at slow leveling speed.

8. In combination; an elevator car; a hoisting motor for said car; a generator for supplying current to said motor, said generator having a field winding; a source of current for said field winding; means for causing said motor to operate the car between landings, said means comprising a switch operable from one position to another to cause current to be supplied from said source through said winding in one direction to cause said generator to apply voltage to said motor of a polarity to cause movement of said car in a certain direction, and a second switch operable from one position to another to cause current to be supplied from said source through said winding in the other direction to cause said generator to apply voltage to said motor of opposite polarity to cause movement of said car in the opposite direction; and means for causing the car to be brought to a level with a landing in stopping, said leveling means comprising means operable, regardless of whether the car underruns or overruns the landing, to cause the reconnection of said winding to said source in such manner that the current through the winding for only half of the generator pole pieces is reversed to cause the first named switch to be maintained in its other position in the event that the car has been traveling in said certain direction and to cause the return of the second switch to its one position and the operation of the first

named switch from its one to its other position in the event that the car has been traveling in said opposite direction.

In testimony whereof, I have signed my name to this specification.

ANTHONY PINTO.
